US00D599805S

(12) **United States Design Patent**
Perrier et al.

(10) **Patent No.:** US D599,805 S
(45) **Date of Patent:** ** Sep. 8, 2009

(54) **STORAGE DEVICE**

(75) Inventors: **R. Sylvain Perrier**, Ottawa (CA); **Jeremy List**, Ottawa (CA); **Cliff Read**, Carp (CA); **Jason Busschaert**, Towson, MD (US); **Mark Edey**, Ottawa (CA); **James D. Miller**, Holland Landing (CA); **Howard W. Overland**, Aurora (CA)

(73) Assignee: **Springboard Retail Networks Licensing SRL** (BB)

(**) Term: **14 Years**

(21) Appl. No.: **29/300,365**

(22) Filed: **Mar. 19, 2008**

Related U.S. Application Data

(62) Division of application No. 29/241,457, filed on Oct. 28, 2005, now Pat. No. Des. 567,239.

(30) **Foreign Application Priority Data**

Apr. 29, 2005 (CA) 110970

(51) **LOC (9) Cl.** **14-99**

(52) **U.S. Cl.** **D14/480.5**

(58) **Field of Classification Search** D14/436, D14/411, 384-5, 518, 348, 432-5, 299, 167, D14/402, 242, 356, 496, 156, 240; 439/518, 439/139, 141, 144, 140, 638; 710/74, 62; 361/684, 679.31

(57) **CLAIM**

The ornamental design for a storage device, as shown and described.

DESCRIPTION

FIG. 1 is a top perspective view of a first embodiment of the storage device;

FIG. 2 is a bottom perspective view of the storage device of FIG. 1;

FIG. 3 is a top plan view of the storage device of FIG. 1;

FIG. 4 is a bottom plan view of the storage device of FIG. 1;

FIG. 5 is the left side elevation view of the storage device of FIG. 1;

FIG. 6 is the right side elevation view of the storage device of FIG. 1;

FIG. 7 is rear view of the storage device of FIG. 1; and,

FIG. 8 is the front view of the storage device of FIG. 1.

The broken lines shown are included for the purpose of illustrating unclaimed portions of the design, and form no part of the claimed design.
